United States Patent Office

Des. 207,550
Patented May 2, 1967

207,550

TABLE LAMP

Jorgen de Bang, Box 4605, Nassau, Bahamas

Filed Oct. 17, 1966, Ser. No. 4,373

Term of patent 14 years

(Cl. D48—20)

FIG. 1.

FIG. 2.

FIG. 3.

FIG. 4.

I claim:

The ornamental design for a table lamp, substantially as shown.
